Primary Examiner — Sheryl Lane
Assistant Examiner — Nicole C Shiflet(74) *Attorney, Agent, or Firm* — TraskBritt(57) **CLAIM**

The ornamental design for a grill leg, as shown and described.

DESCRIPTION

FIG. 1 is a front left perspective view of a grill leg showing the new design in a grilling environment;

FIG. 2 is a bottom front left perspective view of the grill leg shown in FIG. 1, removed from the grilling environment;

FIG. 3 is a top rear left perspective view thereof;

FIG. 4 is a front elevation view thereof;

FIG. 5 is a rear elevation view thereof;

FIG. 6 is a right side elevation view thereof;

FIG. 7 is a left side elevation view thereof;

FIG. 8 is a top plan view thereof; and,

FIG. 9 is a bottom plan view thereof.

The broken lines in the drawings depict environmental subject matter only and form no part of the claimed design.
